United States Patent Office

Des. 222,354

Patented Oct. 19, 1971

222,354

FLAT ROOF DRAIN

Charles J. Foltz, 6660 Shannon Ave., San Diego, Calif. 92115, and Bernard J. Tomonelli, 1320 Sommermount Drive, El Cajon, Calif. 92020

Filed Feb. 16, 1970, Ser. No. 21,449

Term of patent 14 years

Int. Cl. D23—01

U.S. Cl. D23—42

Fig. 1

Fig. 2

Fig. 3

FIG. 1 is a perspective view of a flat roof drain showing our new design;

FIG. 2 is a top plan view thereof;

FIG. 3 is a side elevation view thereof, the other three sides being similar.

We claim:

The ornamental design for a flat roof drain, as shown and described.
